UNITED STATES PATENT OFFICE.

SAMUEL D. BUTTERWORTH, OF LANSING, MICHIGAN.

CARPET-SECURING DEVICE.

Application filed July 14, 1924. Serial No. 725,865.

To all whom it may concern:

Be it known that I, SAMUEL D. BUTTERWORTH, a citizen of the United States, residing at Lansing, in the county of Ingham and State of Michigan, have invented certain new and useful Improvements in Carpet-Securing Devices, of which the following is a specification.

This invention relates to a carpet securing device, and has for its object securing means for clamping carpet to the floor without the use of tacks or other securing devices.

In hotels and office buildings carpets are laid so as to cover the entire floor area, and it has been customary to tack the carpet down by folding the outer edge under and accurately fitting the carpet to the room. This is a tedious and exacting job, and necessitates the employment of rather careful workmen with the resulting high labor cost in laying the carpet. It is necessary to cut the carpet accurately and to exactly fit the carpet to the room. With my device, however, there is considerable leeway allowed in cutting the carpet and my securing device which eliminates the tacking of the carpet to the floor lessens the labor cost of laying the carpet considerably.

Another advantage of my securing device is that the carpet may be removed from the floor as quickly as the same is laid. When the carpets are tacked it is quite a job to remove all the tacks to take the carpet away to be cleaned. With my device, however, it is merely a few minutes' job to release the carpet so that the same may be removed from the floor to be cleaned and may be secured again in place without entailing a riveting of the carpet to the room, as is necessary when the carpet is tacked. A tacked carpet needs to be stretched and fitted to the room—an operation which must be repeated again when the carpet is re-laid after cleaning or renovating.

In most hotel constructions the floors are made of poured concrete. A nailing strip is usually moulded into the floor by the building contractor, and this is quite a complicated job. The floor must be poured to a level about one inch below the level of the floor; the nailing strip is then laid about the edge of the room and a final layer of concrete is poured within the room inside of the nailing strips to bring the level of the floor up to the level of the nailing strip. With my device, however, the floor may be

poured in one operation, thus eliminating this extra pouring after the nailing strip is located. My construction eliminates the nailing strip, as the carpet is not tacked. Another advantage with my construction is that the baseboard is made of two parts, one of which is built into the building by the contractor, and the other part of the baseboard, which is a clamping member, is supplied by the carpet contractor, and both parts of the baseboard cooperate together to form a final baseboard for the room, as the same are designed so as to fit together and eliminate any fitting or relocating by the contractor of the baseboard after the carpet is laid.

In the drawings:

Fig. 1 is a vertical sectional view through the corner of the room showing the base board and floor construction, showing how my clamping strip is secured in place.

Fig. 2 is a view similar to Fig. 1, but showing the clamping strip before it is sprung into place.

Fig. 3 is a sectional perspective view of a modified construction wherein a metal baseboard and clamping strip are used.

Fig. 4 is a vertical sectional view of the construction as shown in Fig. 3 and showing the means whereby the clamping strip may be removed to release the carpet when the same is to be removed.

In Figs. 1 and 2, I show a baseboard constructed of a fibrous material, such as wood. This baseboard comprises the upper strip *a*, which is anchored to the wall of the lower clamping strip *b*. In most hotels the walls are formed of a hollow fireproof tile designated *c* and the tiles adjacent the floor are provided with the furring *d* and the grounds *e* which are formed of strips of wood laid horizontally and secured to the furring carried by the fireproof tile. The upper member of the baseboard *a* may be nailed to these grounds or wood strips, the nails passing therethrough and into the furring. This will space the base board from the fireproof tile so that the wall plaster *f* when plastered to the tile will come flush with the back of the baseboard. This method of securing the baseboard to the wall is old, and my improvement resides in the clamping strip which is part of my new form of baseboard construction.

My baseboard which comprises the two members *a* and *b* as described, is clearly

shown in Figs. 1 and 2, wherein the upper portion *a* of the baseboard is spaced from the floor *g*. Secured to the floor or moulded therein is a concave rib or ridge *h*. Obviously this rib may be secured to the floor by some other fastening means than that shown in the drawings. In the drawings I show the lower edge of the rib dove-tail so that the same will be anchored in the concrete 10 floor when the concrete is poured. The lower edge of the upper baseboard part *a* is provided with a groove *i* and the bevelled corner edge *j*. The clamping strip *b* is provided with a groove *k* and a tongue *m*, which, 15 when sprung into place, is adapted to fit the tongue and groove carried by the upper baseboard part *a*.

In laying the carpet a thick layer of felt or other padding *n* is laid over the concrete 20 floor and roughly fits the room and is cut so that the same will not extend over the ridge or rib *h* in the floor. The carpet *o* is now laid over this padding and is of greater dimensions than the padding so that the edge 25 of the carpet extends over the rib *h* carried by the floor. The lower edge of the clamping strip *b* is provided with a groove *p* which is complementary to the rounded contour of the rib or ridge *h*. As clearly shown 30 in Fig. 2 this clamping strip is set on the carpet over the rib *h*. A board *q*, three or four feet in length, has one edge resting on the floor at a point removed from the wall and the other edge engaging the top outer 35 edge of the clamping strip. The man who is laying the carpet can then place his foot on this board and by bearing his weight thereon may force the clamping strip into place, the carpet giving sufficiently to allow 40 the same to be sprung under the baseboard part *a*, whereupon the tongue and groove connection between the two parts of the baseboard cooperating with the rib *h*, consequently anchoring the edge of the carpet and 45 clamping the same to the floor. As shown in Fig. 1 it may be seen how this carpet is turned and clamped between the rib and the concave or grooved portion of the clamping strip, thereby preventing the carpet from slipping. 50

In Figs. 3 and 4 I show the preferred form of my construction in which the baseboard is formed of sheet metal. This baseboard is formed of two parts, *a*¹ and *b*¹, the upper 55 part of the baseboard *a*¹ is secured to the furring by nails or other fastening devices *r*, as shown in Fig. 4. This portion of the baseboard is provided with a lower extension which terminates in the roll or rib *t* and the entire baseboard section is formed in such 60 a way as to provide a channel which faces towards the center of the room. The upper wall of said channel is provided with a tongue *u* which runs lengthwise to the baseboard section. The clamping strip *b*¹ is also

formed of sheet metal and is substantially U-shaped in cross section; the top leg of said clamping strip provided with a groove *u*¹ adapted to engage the tongue *u* carried by the other baseboard section. The lower 70 leg of the clamping strip is formed with a groove *t*¹ cooperating with the roll or rib *t* of the other baseboard section.

The padding *n* is laid on the floor the same 75 way as above described and the carpet *o* is laid over the padding and has a greater dimension than the padding so that the edge of the carpet will extend into the channel formed by the first-mentioned baseboard section *a*¹. The clamping strip is sprung into 80 place in the same manner as is the wood clamping strip *b* shown in Figs. 1 and 2.

In Fig. 4 I show a means whereby this clamping strip may be removed to release 85 the carpet. I use the same plank *q* but provide a block *v* which may be laid on the floor at a point removed from the wall so as to raise the fulcrum point of the plank *q* above the top edge of the clamping strip. A pressure on this plank will cause the same to 90 bear down on the clamping strip in the direction as shown by the arrow, the components of said force exerting a downward pressure on the clamping member and a pressure tending to force the same away 95 from the stationary baseboard section *a*¹. Obviously this will further compress the carpet until the tongue and groove connection *u* and *u*¹ between the clamping strip *b*¹ and the stationary baseboard section *a*¹ may 100 separate to allow the clamping strip to be slipped out and removed whereupon the carpet may be bodily removed from the room.

With such a sheet metal baseboard construction, the section *a*¹ may be secured in 105 place by the contractor and the roll *t* and the tongue *u* are permanently and definitely located. The carpet contractor may insert the other part of the baseboard, to-wit: the clamping strip *b*¹. 110

With the use of this construction the carpet is quickly laid and is better secured to the floor. All tacks or fastening devices are eliminated, thus allowing the carpet to be removed at any time with very little labor. 115 In addition it is unnecessary to accurately cut the carpet as there is sufficient space behind the clamping strip so as to allow quite a variation in the size of the carpet.

What I claim is:

1. A carpet securing device, comprising a baseboard and a clamping strip secured thereto by a tongue and groove arrangement said clamping strip adapted to grip the edge of the carpet to clamp the carpet to the floor. 125

2. In a carpet securing device, the combination of a baseboard provided with a removable clamping member and a rib rigidly supported on the floor, the said clamping member adapted to be wedged between the 130

body of the baseboard and the rib to grip the edge of the carpet to clamp the carpet between the rib and clamping member.

3. In a carpet securing device, the combination of a baseboard provided with a removable clamping member, and a rib rigidly supported on the floor, the said clamping member provided with a groove which straddles said rib whereby the outer edge of 10 the carpet is clamped between the rib and clamping member, the said clamping member wedging between the bottom of the baseboard and the carpet over the rib.

4. A carpet securing device, comprising a 15 baseboard provided with a channel facing towards the inside of the room and adjacent the floor, said channel adapted to receive the edge of the carpet, and a clamping strip detachably secured to said baseboard for forcing into the mouth of said channel for the 20 purpose of clamping the carpet to the floor by its crowding action.

5. A carpet securing device comprising a 25 baseboard of sheet metal, and formed with a channel facing towards the inside of the room and adapted to receive the edge of the carpet, and a clamping strip of sheet metal 30 U-shaped in cross section, one of the legs of said clamping strip engaging the upper wall of said channel and the other leg and the clamping strip adapted to clamp the carpet between it and the lower wall of said channel.

6. A carpet securing device, comprising a 35 baseboard of sheet metal and formed with a channel facing towards the inside of the room, the lower edge of said channel terminating in a roll adjacent the floor, said channel adapted to receive the outer edge of the carpet, and a clamping member for closing 40

the mouth of said channel to clamp the carpet over the roll.

7. A carpet securing device, comprising a baseboard of sheet metal provided with a channel the lower edge of said channel terminating in a roll adjacent the floor, the 45 said channel adapted to receive the edge of the carpet, and a clamping strip U-shaped in cross section, the bottom leg of which is grooved to straddle said roll formed in the 50 baseboard section, the said carpet adapted to be clamped between the roll and the grooved leg of said clamping strip.

8. A carpet securing device, comprising a baseboard provided with a channel facing 55 towards the inside of the roll, and adapted to receive the edge of the carpet and the upper wall of said channel provided with a tongue and a clamping member provided with a groove for engaging the tongue and 60 arranged to clamp the carpet to the floor.

9. A carpet securing device, comprising a baseboard rigidly secured to the wall and provided with a channel facing towards the 65 inside of the room and adapted to receive the edge of the carpet, and a clamping strip for wedging into the mouth of said channel and clamping the carpet to the floor.

10. A carpet securing device, comprising a baseboard rigidly secured to the wall, and 70 provided with a channel facing towards the inside of the room and adapted to receive the edge of the carpet, and a clamping strip for closing the mouth of said channel arranged to be wedged therein to clamp the 75 carpet to the floor.

In testimony whereof I have affixed my signature.

SAMUEL D. BUTTERWORTH.
